UNITED STATES PATENT OFFICE.

GILBERT WRIGHT, OF PITTSFIELD, MASSACHUSETTS, ASSIGNOR, BY MESNE ASSIGNMENTS, TO GENERAL ELECTRIC COMPANY, A CORPORATION OF NEW YORK.

RECEPTACLE AND PLUG.

1,171,914.

Specification of Letters Patent. Patented Feb. 15, 1916.

Application filed August 13, 1906. Serial No. 330,293.

To all whom it may concern:

Be it known that I, GILBERT WRIGHT, a citizen of the United States, residing at Pittsfield, in the county of Berkshire and State of Massachusetts, have invented certain new and useful Improvements in Receptacles and Plugs, of which the following is a specification.

The present invention relates to electric wiring devices and more especially to receptacles and attaching plugs, whereby a branch circuit conductor may be readily connected to and disconnected from the main circuit conductors.

15 The receptacles are ordinarily inserted in a hole in the wall or ceiling of a room and are provided with contacts permanently connected to the supply circuit and the plugs are connected to the ends of the wires of 20 portable translating devices, such as fan motors, heating apparatus, lamps, etc., and provided with contacts adapted to detachably engage the contacts on the receptacles so as to complete the electric circuit through the 25 translating device.

The receptacles are customarily provided with flush wall plates with openings through which the plugs are inserted to make connection with the contacts carried thereby, and 30 doors or shutters are provided for closing the openings when the plugs are removed.

Doors as ordinarily used are objectionable on account of the liability of their being left open and projecting out from the 35 plate and presenting unsightly appearance and often causing injury by their sharp unprotected corners, and the other forms of shutters heretofore in use are objectionable on account of their preventing the complete 40 insertion of the plug so that a considerable portion thereof projects out from the face plate presenting an obstruction with which persons or objects are liable to come in contact to the injury of the contacts or the person or object.

The object of my invention is to provide an improved construction of receptacle and attaching plug whereby a pleasing and artistic appearance is presented whether the 50 parts are coupled or disengaged and the objections above pointed out effectually avoided.

In the accompanying drawing forming a part of this specification is shown one embodiment of my invention.

Figure 1 is a front elevation of the receptacle and plug in coupled relation; Fig. 2 is a central vertical section of the same with the plug detached; Fig. 3 is a transverse section on line 3—3 of Fig. 2; Fig. 4 is 60 a front elevation of the receptacle with the wall plate removed; Fig. 5 is a central transverse section of the plug; and Fig. 6 is a perspective view of one of the plug contacts removed.

65 The receptacle comprises a box 1 of porcelain or other insulating material with a central cylindrical chamber 2 in its bottom portion, and on opposite sides thereof metal contacts 3 are secured by screws 4 extending 70 through the bottom portion. The metal contacts 3 are in the form of flat metal bars which project outwardly at right angles to the bottom of the box and have attaching feet extending along the inner surface of 75 the bottom and connect with cylindrical binding posts 5 disposed in diagonally opposite corners of the box and provided at their outer ends with screws 6 for engaging the current supply wires which enter the 80 box 1 through holes or recesses in the outer edge thereof. At each end of the box is an attaching lug 7 by which the box may be attached to the wall or other support, and connected to the box by screws 8 extending 85 through holes formed in the end walls thereof. The inner edges of the lugs 7 are extended inwardly at 9 to form stops for the shutter 10. The shutter consists of a block 90 of insulating material of a shape to correspond with the cross section of the plug and having two transverse apertures 11 of a size to permit the stationary contacts 3 to pass freely therethrough, and the outer ends of said apertures are countersunk at 12 to facilitate the positioning of the plug in relation to the shutter.

95 The shutter has integral therewith or attached thereto, two guide blocks 13 which project rearwardly from diagonally opposite points and engage at their sides with the inner surfaces of the side and end walls of the box 1 to maintain the shutter in proper relation with the stationary contacts, and the outer ends of said guide projections are set back from the outer surface of the shutter so that upon coming in contact with the stops 9 the shutter will be arrested in proper position with relation to the face plate. Arranged at the center of the back side of the 100 105 110

shutter is an insulating guide sleeve 14 for the spring 15 which thrusts against the inner ends of the sleeve 14 and the cylindrical chamber 2 in the bottom of the box to normally maintain the shutter in its outer position, as shown in Fig. 2 of the drawing.

The face plate 16 is of usual construction, and at the center it is provided with an aperture 17 corresponding to the cross section of the plug.

The attaching plug consists of a base portion 18 of insulating material and a detachable cap 19 of sheet metal. The outer end of the plug is chambered at 20 and the inner end has two transverse recesses 21 formed therein for the reception of the contacts 22. The plug contacts each consist of an attaching plate 23 having tapped holes 24 in its ends for the reception of the screws 25 which extend through the base portion 18, and integral contact clips 26 are bent up from opposite sides so that their adjacent faces are parallel for a greater portion of their length and sufficiently near together to frictionally engage the opposite sides of a stationary contact 3. A binding post 27 is secured to the back of the plate 23 and a U-shaped yoke 28 is secured to the front surface thereof between the clips 26. The free ends of the U-shaped yoke are provided with gripping jaws 29 adapted to engage notches 30, cut in the edges of the contacts 3, when the plug is in coupled position and serve to effectually prevent its displacement by the action of the spring 15. The outer ends of the binding posts 27 are provided with screws 31 for securing thereto the ends of the branch circuit conductors 32. The cap 19 is cup-shaped with a central opening 33 for the passage of the branch conductors 32 and has attaching ears 34 on opposite sides which are engaged by screws 35 extending therethrough and entering a tapped block 36 located in a transverse recess in the base portion 18 of the plug.

It is to be noted that the construction of my device is such that by pulling upon the branch conductors 32 of the plug when in coupled position sufficiently to overcome the grip of the jaws 29, a snap break between the contacts of the plug and receptacle will be effected by the sudden recoil of the shutter spring 15 and that the shutter 10 in its normal position stands sufficiently forward of the ends of the stationary contacts 3 to effectually prevent an object from accidentally coming in contact therewith.

I do not desire to restrict myself to the particular form or arrangement of parts herein shown and described, since it is apparent that they may be changed and modified without departing from my invention.

What I claim as new and desire to claim by Letters Patent of the United States, is,

1. A receptacle having a side opening, a

plurality of stationary contacts therein opposite said opening, and an outwardly impelled shutter provided with apertures through which the contacts protrude upon displacement of the shutter.

70

2. A receptacle having a side opening, a plurality of stationary contacts therein opposite to and below said opening, and a spring-pressed shutter of insulating material displaceable within said receptacle and provided with apertures through which the contacts protrude upon displacement of the shutter.

75

3. A receptacle having a side opening, contacts secured wholly within said receptacle and projecting part way toward said opening, a spring-pressed shutter displaceable within said receptacle and provided with means for guiding it therein and with means whereby the contacts may protrude therethrough upon displacement thereof.

80

4. A receptacle having a side opening, a cylindrical chamber formed therein opposite said opening, contacts secured on opposite sides of said chamber, a shutter of insulating material for said opening displaceable within said receptacle and provided with apertures through which the contacts protrude upon displacement of the shutter, and a spring seated in said chamber and pressing said shutter outwardly.

90

5. A receptacle having a parallel-sided box portion, two stationary contacts secured to the bottom thereof, binding posts connected to said contacts and disposed in diagonally opposite corners of the box, and a shutter displaceable within said receptacle and having two guide projections adapted to engage the other diagonally opposite corners of the box.

100

6. A receptacle having a side opening, stationary contacts in said receptacle, an inwardly displaceable shutter for said opening provided with apertures in alignment with the said contacts, a plug having contacts adapted to engage said stationary contacts, and means on the shutter for positioning said plug relatively to said apertures.

105

7. A receptacle having a side opening, stationary contacts in said receptacle extending toward said opening, a spring-pressed shutter for closing said opening and normally inclosing said stationary contacts, and a plug provided with jaws adapted to engage said contacts upon insertion of the plug.

115

8. In a device of the class described, a face-plate provided with an aperture, a downwardly-extending hollow member having a pair of fixed contacts on the base thereof, means to normally close the aperture in the face-plate, said hollow member adapted to act as a guide for said means.

120

9. In a device of the class described, a

130

receptacle, fixed contacts carried by the base of said receptacle, a face-plate having an aperture, means on the receptacle between the face-plate and the base of the receptacle to act as a guide for a shutter, a shutter adapted only for rectilinear movement to normally close the aperture in the face-plate, the shutter having sliding contact with the means located between the face-plate and the base of the receptacle so that the shutter may be guided by said means.

10. In a device of the class described, a receptacle, a face-plate having an aperture surrounded by the wall of the receptacle, fixed contact members mounted on the base of said receptacle, a shutter normally inclosing said fixed contacts and adapted to have only a rectilinear movement and be

guided in such movement by the wall of 20 the receptacle, means for normally pressing the shutter outward, and means for limiting such outward movement of the shutter.

11. A box or receptacle of the class described having a face-plate provided with an opening, a wall surrounding the opening, and closure means guided by the said wall and always closing the interior of the box or receptacle in whatever position the 30 closure means may be.

In witness whereof, I have hereunto set my hand this ninth day of August, 1906.

GILBERT WRIGHT.
